INVENTOR.

UNITED STATES PATENT OFFICE

161,707

SPORT SANDAL

Howard Peterson, Newport News, Va.

Application September 25, 1950, Serial No. 12,352

Term of patent 14 years

(Cl. D7—7)

To all whom it may concern:

Be it known that I, Howard Peterson, a citizen of the United States, residing at Newport News, in the county of Warwick and State of Virginia, have invented a new, original, and ornamental Design for a Sport Sandal, of which the following is a specification, reference being had to the accompanying drawing, forming part thereof.

Fig. 1 is a side perspective view of a sport sandal, showing my new design;

Fig. 2 is a bottom perspective view thereon.

I claim:

The ornamental design for a sport sandal, substantially as shown.

HOWARD PETERSON.
